SILENCER

Sidney Oldberg, Detroit, Mich.

Application July 25, 1934, Serial No. 736,861

5 Claims. (Cl. 137—160)

This invention relates to silencers and more particularly to silencers used in connection with gases exhausted from internal combustion engines.

In the Oldberg Patent 1,950,455, dated March 13, 1934, there is disclosed a multiple pass silencer having an outer shell or casing containing several resonance units, including an inner through shell and an intermediate shell. Inasmuch as the construction of that patent requires two shells for each unit, a triple pass silencer of that construction requires seven shells in all. Therefore, that construction, while extremely effective as a silencer, has proven to be somewhat more expensive than is considered desirable for certain classes of purchasers, and for this reason it is now proposed to provide a multiple pass silencer which is lighter in weight and less expensive in construction than the silencer of that patent, but which, despite its being provided with less parts than the silencer of that patent, is efficient and satisfactory for the use to which it is put.

Detailed objects of the invention will be readily apparent to those skilled in the art upon reference to the following detailed description of embodiments of the same, reference being had to the appended drawings which show these embodiments.

In these drawings:

Figure 1 is an elevational section view of one form of silencer, as if on the line 1—1 of Figure 2;

Figure 2 is a transverse section as if on the line 2—2 of Figure 1;

Figures 3 and 4 are similar views of a second embodiment; and

Figures 5a to 5d collectively show the shells and plates of the embodiment shown in Figures 3 and 4.

Figure 6 is a transverse section view of a third embodiment.

Referring to Figures 1 and 2 of the drawings, it will be seen that the silencer there shown includes an imperforate outer shell or casing 10 and a plurality of shells referenced 12, 14, and 16, nested within one another and within the outer shell or casing 10. The casing 10 is closed at its ends by inlet and outlet end headers 18 and 19.

The innermost shell 12 and the outer shell or casing 10 are of circular cross section, whereas the intermediate shells 14 and 16 are of elliptical cross section, these being so dimensioned and arranged that the planes of their major axes coincide with each other and with a diametrical plane of the outer shell. When the shells are assembled

in the desired manner, as shown in Figure 2, the intermediate shells tangentially engage each other and the outer shell along lines referenced X, which lines represent lines of welding for mutually securing the intermediate shells and the outer shell in a rigid unitary assembly.

By virtue of this construction it will be readily observed that the innermost shell 12 is spaced from the intermediate shell 14 by a space 20 which varies in transverse dimension from a small dimension at the minor axis of the intermediate shell 14 to a large dimension at the major axis of the intermediate shell 14. Intermediate shell 14 is spaced from intermediate shell 16 by two relatively isolated crescent-shaped spaces 21—22, and intermediate shell 16 is spaced from the outer shell 10 by two relatively isolated crescent-shaped spaces 23—24.

The innermost shell 12 is provided with a large area of minute perforations 26 which open into the space 20, and in the space 20 there are provided diaphragms 27 which divide the space 20 into a plurality of longitudinally separated sound absorption chambers.

One end of the innermost shell 12 passes through the inlet header 18 and is open at that end to provide an inlet for the silencer. The other end of the innermost shell 12 opens into an expansion chamber 28 within the intermediate shell 14, this chamber being closed by a plug 30 at a point longitudinally spaced from the end of the innermost shell 12.

The lower half only of the intermediate shell 14, at the expansion chamber 28 between the end of shell 12 and the plug 30, is provided with a large number of relatively large openings or throats 31, whose aggregate cross section area is intentionally much larger than the cross-sectional area of the innermost shell 12. These throats communicate without substantial restriction the interior of the expansion chamber 28 with the space 21 between the shells 14 and 16. The lower half of the shell 16, between the throats 31 and the inlet end of the shell 14, and the upper half thereof, between the inlet end of the shell 14 and the plug 30, are provided with large areas of minute perforations 32, these communicating the relatively sealed spaces 21—22 with the relatively sealed absorption chambers 23—24, it being observed that the spaces 21—22 are sealed and isolated from each other, except at the expansion chamber 32a around the inlet end of the innermost shell 12 adjacent the inlet end of the intermediate shell 14.

The upper half of the intermediate shell 14, be-

55

tween the plug 36 and the outlet end thereof which opens through the outlet end header 48, is provided with a large number of relatively large openings or throats 33 which communicate the space 22 with the expansion chamber 34 in the interior of the shell 14 beyond the plug 36.

It will be observed that exhaust gases pass through the silencer in substantially the following path. Gases enter the silencer through the open inlet end of the innermost shell 12 and course through that shell, discharging into the expansion chamber 33; from there they flow with substantially no restriction through the throats 31 into the space 21, coursing through that space to the expansion chamber 32a at the inlet end of the silencer; when they leave chamber 32a, they course through space 22 towards the outlet end of the silencer, from where they pass to expansion chamber 34 through throats 33; from there, they leave the silencer.

During its flow in each course, the gases pass by the absorption chambers provided in and by spaces 20, 23, and 24, and sound waves are absorbed in these absorption chambers.

The silencer here shown is economical of manufacture, and yet efficient for silencing. The stampings which enter into the manufacture of the silencer can be made very easily and cheaply, and the assembly of the shells can be effected at a minimum of cost.

Comparing the silencer here shown with the silencer shown in the patent above referred to, it will be observed that the silencer here shown utilizes four shells to provide a triple pass construction wherein each turn is effected in an unrestricted expansion chamber, and wherein each course is at least partially surrounded by absorption chambers, whereas the construction shown in the patent above referred to requires seven shells to attain similar results.

It will also be observed that the elliptical shape of the shells 14 and 16 is of advantage in that the reflection of the maximum part of the sound from the circular innermost shell 12 to the elliptical intermediate shell 14 does not return sound waves back towards the circular shell 12, but directs them away from the circular shell 12.

Referring to Figures 3-5, it will be seen that they show a triple pass silencer wherein four circular shells and two flat rectangular plates are assembled in a manner to provide a triple pass silencer, with unrestricted turns and with courses surrounded at least partially by absorption chambers.

The silencer of these figures includes an innermost shell 48 concentrically telescoped within an intermediate shell 41, which in turn is eccentrically telescoped within a second intermediate shell 42, there being a plate 43 disposed between the shell 41 and the shell 42, the latter shell in turn being eccentrically telescoped within an outer shell or casing 44, there being a plate 45 disposed between the shells 42 and 44.

Inlet and outlet end headers 47-48 close the ends of the silencer, with the innermost shell 48 having its inlet end passing through a flanged opening of the inlet header to provide an inlet for the silencer and with the outlet end of the intermediate shell 41 passed through a flanged opening of the outlet header 48 and opening therethrough to provide an outlet for the silencer.

The annular space 50 between the innermost shell 48 and the intermediate shell 41 is provided with diaphragms 51 which form an absorption chamber therein, communication between this

chamber and the interior of the innermost shell 48 being effected through a large number of minute perforations 52.

The end of the innermost shell 48 opposite the inlet end thereof opens into an expansion chamber 53 within the intermediate shell 41, and this chamber is closed at a point remote from the aforementioned end of the innermost shell 48 by a plug 53a. The rear half only of the shell 41, at the expansion chamber 53, is provided with a large number of relatively large openings or throats 54 and these communicate the interior of the expansion chamber, with substantially no restriction, with the space 55 between the shell 41 and the shell 42, behind the plate 43. The plate 43, near its inlet end, is provided with a relatively large number of openings or throats 56 which communicate the space 55, near its inlet end, with the space 57 between the shells 41-42, and in front of the plate 43, the throats 56 being large enough individually and in aggregate to present substantially no restriction to the flow of gases from space 55 to space 57.

The outlet end of the shell 41 on the front half thereof only, and between plug 53a and the outlet header 48 is provided with a large number of relatively large openings or throats 58 which communicate the space 57, near the outlet end of the silencer, with the interior of shell 41 beyond the plug 54, from where the gases leave the silencer.

It will be observed that gases entering the silencer through the open inlet end of the innermost shell 48 course through that shell, passing the absorption space 50, and discharge into expansion chamber 53. From there the gases pass into space 55 near the outlet end of the silencer and course back towards the inlet end of the silencer, passing absorption space 59 which communicates with the coursing space 55 through a large area of minute perforations 60; the gases leave space 55 through throats 66 and enter space 57 near the inlet end of the silencer, coursing through that space past the absorption space 61 which communicates therewith through a large number of minute holes 62, until they reach throats 58 in the shell 41; the gases then leave the silencer through these throats and the outlet end of shell 41.

The construction here shown, while it includes, in addition to the parts shown in the silencer of Figures 1-2, the two plates 43 and 45, is nevertheless extremely economical of manufacture without being inefficient for silencing.

In Figure 6 there is shown a silencer of the type shown in Figure 4, but wherein the shells 40, 41, 42, and 44 are so arranged that the flat plates 43, 45, which divide the shells 42, 44, longitudinally are adjacent, rather than diametrically opposed. This arrangement may be used if preferred, though it is substantially like that of Figure 4.

Now having described preferred embodiments of the invention, selected by way of example, reference will be had to the claims which follow for a determination of the scope of the invention.

What I claim is:

1. A triple pass silencer characterized by its having a shell and space arrangement including four relatively telescoped shells which will be hereinafter referred to as shells *a*, *b*, *c*, and *d*, of which shell *a* is within shell *b*, and is separated therefrom by space *a-b*, shell *b* is within shell *c*, and is separated therefrom by space *b-c*, and shell *c* is within shell *d*, and is separated therefrom by space *c-d*, the interior of shell *a* providing the first gas pass from the inlet end of the

silencer, shell *a* being perforated so that its interior communicates with the space *a*—*b* so that the latter space may provide a silencer space for the first gas pass, one half of space *b*—*c* providing the second gas pass, communication between the first and second gas passes being through shell *b* at a point beyond the end of shell *a*, the part of shell *c* adjacent the half of space *b*—*c* that provides the second pass being perforated to communicate that half of space *b*—*c* with the adjacent half of space *c*—*d* so that the latter space may provide a silencer space for the second gas pass, the other half of space *b*—*c* providing the third gas pass, communication between the second and third gas passes being effected near the inlet end of the silencer, the part of shell *c* adjacent the half of space *b*—*c* that provides the third pass being perforated to communicate that half of space *b*—*c* with the adjacent half of space *c*—*d* so that the latter space may provide a silencer space for the third gas pass.

2. A triple pass silencer characterized by its having a shell and space arrangement including four relatively telescoped shells which will be hereinafter referred to as shells *a*, *b*, *c*, and *d*, of which shell *a* is within shell *b*, and is separated therefrom by space *a*—*b*, shell *b* is within shell *c*, and is separated therefrom by space *b*—*c*, and shell *c* is within shell *d*, and is separated therefrom by space *c*—*d*, shell *a* terminating short of shell *b*, shell *b* having a transverse closure between the end of shell *a* and its own end and having openings on opposite sides thereof and on opposite sides of the closure, shell *a* being perforated throughout its length, shell *c* being perforated throughout the length thereof between a point near the inlet end of the silencer and a point near the closure of shell *b*, shells *c* and *d* being closed at their ends by end headers, space *a*—*b* being closed at its ends, shell *a* being open at its ends, and shell *b* being open at the end thereof remote from shell *a*, a longitudinally extending plate in space *b*—*c* dividing it into two longitudinal halves and having apertures at the inlet end of the silencer communicating the halves, and a longitudinally extending plate in space *c*—*d* dividing it into two longitudinally isolated halves.

3. A triple pass silencer characterized by its having a shell and space arrangement including four relatively telescoped shells which will be hereinafter referred to as shells *a*, *b*, *c*, and *d*, of which shell *a* is within shell *b*, and is separated therefrom by space *a*—*b*, shell *b* is within shell *c*, and is separated therefrom by space *b*—*c*, and shell *c* is within shell *d*, and is separated therefrom by space *c*—*d*, shell *a* terminating short of shell *b*, shell *b* having a transverse closure between the end of shell *a* and its own end and having openings on opposite sides thereof and on opposite sides of the closure, shell *a* being

perforated throughout its length, shell *c* being perforated throughout the length thereof between a point near the inlet end of the silencer and a point near the closure of shell *b*, shells *c* and *d* being closed at their ends by end headers, space *a*—*b* being closed at its ends, shell *a* being open at its ends, and shell *b* being open at the end thereof remote from shell *a*, a longitudinally extending plate in space *b*—*c* dividing it into two longitudinal halves and having apertures at the inlet end of the silencer communicating the halves, and a longitudinally extending plate in space *c*—*d* dividing it into two longitudinally isolated halves.

4. A triple pass silencer characterized by its having a shell and space arrangement including four relatively telescoped shells which will be hereinafter referred to as shells *a*, *b*, *c*, and *d*, shell *a* being utilized as the first pass, shell *a* being positioned within shell *b* so that the space therebetween forms a silencer chamber for the first pass, shell *c* being disposed about the combination of shells *a* and *b* to form a space between shells *b* and *c*, means to divide the space between shells *b* and *c* into two longitudinally isolated passes communicating at their ends to form a continuous retroverted pass, means in the combination of shells *a* and *b*, to connect the first pass with one end of the continuous pass, shell *d* being disposed about the combination of shells *a*, *b*, and *c*, so that the space around shell *c* forms two silencer chambers for the two parts of the continuous pass, communication between shells *a* and *b*, and shells *c* and *d* being provided by perforations in shells *a* and *c*.

5. A triple pass silencer characterized by its having a shell and space arrangement including four relatively telescoped shells which will be hereinafter referred to as shells *a*, *b*, *c*, and *d*, the first pass being formed in shell *a*, shell *b* being disposed about shell *a* so that the space therebetween provides a silencer chamber for the first pass, shell *a* opening into an expansion chamber formed in shell *b*, shell *c* being disposed about shell *b* to form a space therebetween, means in said space to divide the same into the second and third passes, these passes being in communication to form one continuous retroverted pass, one end of which opens to the atmosphere, communication means between the expansion chamber and the other end of the continuous pass, and shell *d* being disposed about shell *c* so that the space around shell *d* forms two silencer chambers for the two parts of the continuous pass, communication between shells *a* and *b*, and shells *c* and *d* being provided by perforations in shells *a* and *c*.

SIDNEY OLDBERG.
